UNITED STATES PATENT OFFICE.

AUGUST C. PRECHEL, OF COTTONWOOD, MINNESOTA, ASSIGNOR OF ONE-HALF TO
THEODORE B. SEIFERT, OF COTTONWOOD, MINNESOTA.

WASHING-MACHINE.

1,243,551.

Specification of Letters Patent. Patented Oct. 16, 1917.

Application filed February 16, 1917. Serial No. 148,994.

To all whom it may concern:

Be it known that I, AUGUST C. PRECHEL, a citizen of the United States of America, residing at Cottonwood, in the county of Lyon and State of Minnesota, have invented certain new and useful Improvements in Washing-Machines; and I do hereby declare the following to be a full, clear, and exact description of the invention, such as will 5 enable others skilled in the art to which it appertains to make and use the same.

This invention relates to washing machines, and the primary object of the invention is to provide a washing machine which includes a rubber which moves longitudinally over a rubbing board, to provide practically the same action as is occasioned by the rubbing of clothes by hand upon an ordinary wash-board, so as to properly 10 cleanse the clothes.

Another object of this invention is to provide a washing machine as specified which includes a detergent liquid retainer in which is mounted a rubbing board, and 15 a rotary rubber which is adapted to rotate and move longitudinally over the surface of the rubbing board.

Another object of this invention is to provide a pivotally mounted handle to 20 which is connected the arm of the rotary rubber so that upon pivotal movement of the lever or handle the rubber will be moved longitudinally over the surface, and further to provide a rack bar and pinion construction for rotating the rubber during its 25 movement over the rubbing board.

A still further object of this invention is to provide a power transmitting structure, or a power balancing structure which is attached to the under surface of the detergent liquid retaining receptacle and includes a 30 pair of gears and a balance wheel, to one of which gears an arm is connected, which arm is connected to the pivotally mounted 35 lever for transmitting power to the lever, or for balancing the movement of the lever and increasing its momentum.

With the foregoing and other objects in view, this invention consists in such novel 40 features of construction, combination and arrangement of parts as will be hereinafter more fully described, illustrated in the accompanying drawings and claimed.

In describing the invention in detail reference will be had to the accompanying drawings wherein like characters designate like and corresponding parts throughout the several views, and in which:—

Figure 1 is a longitudinal section through the improved washing machine; 60

Fig. 2 is a top plan view of the washing machine;

Fig. 3 is a section on the line 3—3 of Fig. 2; and

Fig. 4 is a detail plan of the power transmitting structure.

Referring more particularly to the drawings, 1 designates the detergent liquid retaining receptacle, which is preferably rectangular in shape, and is supported by suitable supporting legs 2. The receptacle 1 may have the usual type of outlet or drain indicated at 3 and its upper side or top is open. The end wall 4 of the receptacle 1 has a drain pan 5 attached thereto, to the 70 outer edge of which is attached a wringer supporting bar 6.

A rubbing-board 7 is mounted within the receptacle 1 and it is constructed of wood or analogous material, comprising a main 80 supporting structure 8 having a plurality of transversely extending bars 9 attached to its upper surface, which are disposed in spaced relation to each other and have their upper surfaces convexly curved so as to 85 provide a proper rubbing surface over which clothes may be rubbed. The rubbing-board 7 is loosely mounted in the receptacle 1 so that it will float upon the water or other liquid within the receptacle. 90

A pair of horizontally positioned rack bars 10 are attached to the inner surfaces of the sides 11 of the receptacle 1 midway of their upper and lower edges and the teeth of the rack bars 10 mesh with the 95 peripheral teeth of pinions 12 which are mounted upon the rubber shaft 13. The rubber 14 is mounted upon the shaft 13 for rotation therewith, and it comprises a pair of end plates 15 which have a plurality of 100 blades 16 attached thereto. The blades 16 radiate from the shaft 13 as clearly shown in Fig. 3 of the drawings and they have their outer edges rounded as shown at 17 to provide curved surfaces for engagement with 105 clothes being washed for eliminating the

liability of tearing the clothes by sharp corners of the rubbing plate. A substantially U-shaped plate 18 has the lower ends of its legs loosely mounted upon the shaft 13 outwardly of the plates 15. The U-shaped plate 18 has a pair of bars 19 and 20 attached thereto and extending along the upper surface of the receptacle 1. The bars 19 and 20 are attached, as indicated at 21 to the upper end of pivoted lever 22. The lever 22 is pivotally connected as shown at 23 to a pair of bars 24. The bars 24 are attached to and extend transversely from a bracing bar 25 which is attached to one pair 26 of the supporting legs 2. A socket 26 is carried by the upper end of the lever 22 and it has a handle 27 removably seated therein, one edge of the inner enlarged end 28 of which engages and lies in facial abutment with a portion of the upper end of one edge of the lever 22 as clearly shown in Fig. 2 of the drawings. When the lever 22 is operated it will move the rubber 14 longitudinally within the receptacle 1 and the peripheral teeth of the pinions 12 meshing with the teeth of the rack bars 10 will rotate the shaft 13 and the rubber 14, causing a rubbing action upon the clothes similar to that administered by hand rubbing upon an ordinary wash-board.

The plates 15 act as guards for preventing the clothes from becoming entangled in and torn by the teeth of the rack bars or of the pinions 12. The plates 15 pass very closely 35 to the rack bars 10 and while the rubber 14 revolves downward, the plates 15 turn down the clothes away from the teeth of the rack bars 10 and the pinions 12 and thus prevent the clothes from getting into the teeth and 40 being torn as well as interfering with the operation of the rubber.

The legs 29 of the plate 18 have pins 30 carried thereby upon which are mounted rollers 31. The rollers 31 are rotatably 45 mounted upon the pins 30 and they engage the under surfaces of guide bars 32 which are carried by the inner surfaces of the sides 11 of the receptacle 1 for preventing the rubber from moving upwardly during its 50 operation.

The lever 22 has an arm 35 connected thereto as shown at 36 which arm is connected to a pin 37. The pin 37 is carried by a gear 38 eccentrically of the center of the gear as clearly shown in Fig. 1 of the drawings, so that the rotation of the gear will move the lever 22 upon its pivot 23. The gear 38 is mounted upon a shaft 39, which is supported by a suitable bearing 40. The bearing 40 is attached to a plate 41 which plate is in turn attached to the under surface of the bottom 42 of the receptacle 1 by suitable hangers 43. The gear 38 meshes with a pinion 44 which is mounted upon a shaft 45. The shaft 45 is supported by a

bearing 46 which is also carried by the plate 41 and it has a balance wheel or pulley 47 mounted thereon upon the opposite edge of the plate 41 from the gear 44. If it is so desired, a belt 48 may be passed about the balance wheel 47 for transmitting power from any suitable power source to the shaft 45 and consequently to the shaft 39 and the gear 38 through the meshing engagement of the gear 38 with the pinion 44 for operating the lever 22 and the washing machine by a suitable prime mover.

If it is desired to manually operate the washing machine, the gear 38, pinion 44 and balance wheel 47 act as a momentum increaser for the operation of the lever 22 and consequently increase the ease with which the lever may be operated.

In washing clothes; the water having the necessary detergent ingredients or matters 35 therein is placed in the receptacle 1 and the clothes to be washed are placed upon the rubbing board 7 after which the lever 22 is oscillated either by manual power, transmitted through the medium of the handle 27 or by the power of a prime mover transmitted through the pulley or balance wheel 47, pinion 44 and gear 38. The oscillatory movement of the lever 22 will move the rubber 14 longitudinally through the receptacle 95 1 over the rubbing board 7, and the meshing engagement between the rack teeth of the 100 rack bar 10 and the peripheral teeth of the pinions 12 will rotate the rubber at the same time that it is moved longitudinally through the receptacle, thus administering a rubbing action to the clothes quite similar to the rubbing action administered by rubbing the clothes by hand upon an ordinary wash-board.

The rubber 14 performs the function of 105 rubbing, like the hand rubbing on a wash-board, and at the same time acts similar to a vacuum washer, creating a vacuum between the blades 16 and plates 15, while the rubber 14 rotates, causing a compression which forces the water through the clothes being washed. If it is so desired, the floating rubbing board 7 may be removed and the machine used as a vacuum washer, without departing from the spirit of this invention.

From the foregoing description taken in connection with the accompanying drawings, the advantages of construction and of the 120 method of operation of the improved washing machine will be readily apparent to those skilled in the art to which this invention appertains and, while in the foregoing description, the principle of the operation 125 of this invention has been described together with various features of construction, it is to be understood that certain minor features of construction, combination and arrangement of parts may be altered to suit prac- 130

tical conditions provided such alterations are comprehended within the scope of what is claimed.

What is claimed is:—

- 5 1. In a washing machine structure, a retaining receptacle, a floating rubbing board positioned within said receptacle, a pair of rack bars attached to the sides of said receptacle and extending longitudinally therealong, a rubber positioned within said receptacle and including a shaft, a pair of end plates mounted upon said shaft, a plurality of radially extending rubbing plates carried by said end plates and said shaft, pinions mounted upon said shaft and meshing with said rack bars for rotating the rubber, and means for moving said rubber longitudinally over said rubbing board.
- 10 2. In a washing machine structure, a retaining receptacle, a floating rubbing board mounted within said receptacle, a pair of rack bars attached to the inner surface of

the sides of said receptacle, a rubber including a shaft, a pair of end plates carried by said shaft, a plurality of radially extending rubbing plates carried by said end plates and said shaft, pinions mounted upon the ends of said shaft and meshing with the teeth of said rack bars, a U-shaped plate loosely connected to said shaft and extending upwardly over said rubber, a pair of arms connected to said U-shaped plate, a lever pivotally supported by the receptacle, said arms connected to said lever for moving said rubber longitudinally over said rubbing board upon pivotal movement of said lever.

In testimony whereof I affix my signature in presence of two witnesses.

AUGUST C. PRECHEL.
